Primary Examiner — Philip S Hyder*Assistant Examiner* — Ramzi S Almatrahi*(74) Attorney, Agent, or Firm* — Volpe and Koenig, P.C.(57) **CLAIM**

The ornamental design for a monitoring camera housing, as shown and described.

DESCRIPTION

FIG. 1 is a perspective view of a monitoring camera housing showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken lines depict portions of the monitoring camera housing in which the design is embodied that form no part of the claimed design.
